US00D536058S

(12) **United States Design Patent** (10) **Patent No.:** **US D536,058 S**
(45) **Date of Patent:** ** *Jan. 30, 2007

(54) **LANDSCAPE STONE**

(75) Inventor: **Thomas S. Riccobene**, Albuquerque, NM (US)

(73) Assignee: **Riccobene Designs LLC**, Albuquerque, NM (US)

(*) Notice: This patent is subject to a terminal disclaimer.

(**) Term: **14 Years**

(21) Appl. No.: **29/206,883**

(22) Filed: **Jun. 4, 2004**

(51) **LOC (8) Cl.** 23-02

(52) **U.S. Cl.** D23/113

(58) **Field of Classification Search** D25/112-118, D25/164, 2; D21/483-486, 499-500; 404/17, 404/19-20, 27-31, 34-42; 52/102, 596, 574, 52/612, 603-609

See application file for complete search history.

(57) **CLAIM**

The ornamental design for a landscape stone, as shown and described.

DESCRIPTION

FIG. 1 is a perspective view of the landscape stone of the invention;

FIG. 2 is a top plan view thereof.

FIG. 3 is a front elevation view thereof.

FIG. 4 is a left side elevation view thereof.

FIG. 5 is a right side elevation view thereof.

FIG. 6 is a back elevation view thereof.

FIG. 7 is bottom plan view thereof; and,

FIG. 8 is a top plan view of the stone with a multiplicity of stones in broken lines and forming no part of the claimed design.

The features shown broken lines are not a part of the claimed design.

1 Claim, 5 Drawing Sheets
